BENJAMIN P. FORTIN, OF HARTFORD, CONNECTICUT, ASSIGNOR TO UNDERWOOD TYPE-WRITER COMPANY, OF NEW YORK, N. Y., A CORPORATION OF DELAWARE.

TYPE-WRITING MACHINE.

1,237,319.

Specification of Letters Patent. Patented Aug. 21, 1917.

Application filed January 12, 1916. Serial No. 71,606.

To all whom it may concern:

Be it known that I, BENJAMIN P. FORTIN, a citizen of the United States, residing in Hartford, in the county of Hartford and 5 State of Connecticut, have invented certain new and useful Improvements in Type-Writing Machines, of which the following is a specification.

This invention relates principally to type-writing machines for writing upon a number of superposed webs or continuous sheets, especially those which are intended to be torn off in sections from the body of 10 the web, as, for example, when the webs 15 comprise a series of printed forms, each adapted to be removed when the typewriting thereon is completed. In such work it is desirable to employ ink ribbons or carbon sheets interleaved with the webs for making 20 the duplicate copies. A machine of this general character is shown and described in the patent to Wernery & Smith, No. 1,132,055, dated March 16, 1915. In that machine, after a section of web, to compose 25 a printed sheet, has been written, the platen is shifted away from the usual feed rollers to release the web and the interleaved carbon sheets; whereupon, by means of a carbon sheet holder, the carbon sheets are 30 drawn back along the web into position thereon for the printing of the next web section; the web itself being drawn forward a measured distance for removal of the 35 printed section thereof, and the next im- printed section thereof being positioned, with the carbon sheets therein, for the print- ing operation. The same carbon sheets are thus used over and over in the same web form.

40 In certain machines of this general class, the devices for holding the carbon sheets are light, flexible strips of metal, or fingers, to each of which a sheet of carbon is attached, and which are stepped, or set up, one above 45 the other, to allow space for the plies or folds of the web between the same, and to permit of easy return movement of the carbon sheets over the web in replacing the carbon sheets. In certain of such machines 50 these holding strips or fingers are provided at their free or distal ends with cutters for severing from one another the plies of the web, in the section or length thereof next

to be written upon, as the carbon sheet holders are moved back along the web. It 55 is desirable to have the holding strips of thin and light material; yet, if thus rendered sufficiently flexible, they may be bent or drawn onto the web, in such a manner as to bind and tear the web when moved 60 along the web in replacing the carbon sheets; that is to say, unless provision to the contrary is made. An object of the present invention is to provide means for maintaining the proper position and spacing of 65 such flexible holding clips, to prevent binding and injury to the web when the carbon sheets are re-set on the web, or when the plies of the web are cut apart as described. In the preferred embodiment of this feature 70 of the invention, the holding clips are provided at or near their free or distal ends with depending or projecting beads or lugs which bear upon fixed supports, or which may bear upon the adjacent clips or fingers, 75 thus preventing movement of the clips into the web, and maintaining the clips spaced at proper distance apart, when the clips are moved backward over the web.

In some of the machines of this class, the 80 carbon sheet holding devices are detachably secured as a unit to a carriage, so as to be interchangeable thereon; the purpose being to enable the operator to remove such holder with the web and carbon sheets in place 85 thereon, and to substitute another such holder with a web of different forms, and with carbon sheets already interleaved therewith; thus avoiding the delay which would be caused on every such change, by remov- 90 ing the carbon sheets from one web and placing them in another web. A feature of the present invention is an improved means of locking the interchangeable holders to the carriage, and of releasing the same from 95 the carriage when desired. In the preferred form of the invention this lock consists of a blade pivoted on the carriage and adapted to be swung into and out of a retaining groove in a dowel carried by the holder and 100 which has been passed through the carriage body, to interlock the holder and carriage, and to receive the locking blade on the latter.

A further feature of the invention relates 105 to a gage, or graduated device or scale, by

means of which the proper throw of the 5 holders in re-positioning the carbon sheets on the web, after a form sheet thereof has been written, may be determined with accuracy for the particular length of that form sheet; and also to a stop adjustable lengthwise of such scale, and to means for locking the stop in any selected position, automatically to arrest the carriage on 10 which the carbon sheet holders are mounted, as soon as the carriage has received its predetermined throw. This scale is preferably marked off on one of the carriage rails; and the stop is preferably adjustable 15 along such rail, and is locked to the same, or released therefrom, by a simple and novel form of vise or gripping device for this purpose.

Another feature of the invention relates 20 to the means whereby the table, on which the carriage for the carbon sheet holder moves, is attached to the platen carriage, to have letter-feed and return movement therewith, but is nevertheless so cushioned 25 that the platen carriage does not receive injurious shocks from this relatively heavy table when the two are thrown a distance together. This attachment has also the advantage that fine fitting of parts is obviated.

30 Other features and advantages will hereinafter appear.

In the accompanying drawings,

Figure 1 is a perspective view of the invention as applied to an Underwood type-35 writing machine.

Fig. 2 is a cross sectional view of the locking device for the web-holding finger at the rear of the table.

Fig. 3 is a view in longitudinal cross section through the device by which the table is connected to the platen carriage.

Fig. 4 is a side elevation, partly in side elevation, and partly in cross section.

Fig. 5 is a perspective view of one of 45 the interchangeable plates or carbon sheet holders.

Fig. 6 is a perspective view of the carriage for the carbon sheet holders, the locking devices for securing the holder to the 50 carriage being also shown.

Fig. 7 is a perspective view of the adjustable stop for the carbon sheet holder carriage.

Fig. 8 is a perspective view of one of the 55 adjustable lateral gages or guides for the web, located on the holder of Fig. 5.

Fig. 9 is a perspective view of the gage or guide on the paper shelf for alining the web before the same is cut.

60 Referring to the drawings, the platen 10 has an axle 11 which is journaled in a frame having end pieces or arms 12 fast to a rock-shaft 13. The shaft 13 is journaled in the end plates 14 of the platen carriage. The 65 frame for which the shaft 13 serves as a

pivot, is normally held in Fig. 1 position, with the platen down against the usual feed rolls 15 and 16. It is swung from its normal or printing position, as shown in the patent to Wernery and Smith, No. 1,132,055, 70 by means of an arm or handle 17, which latter is also fast to the shaft 13. For locking the platen frame in printing position, the handle 17 carries a pin 18 adapted to be engaged by a hook 19 pivotally mounted on 75 a bracket 20 on the left-hand end plate 14 of the platen carriage. A spring 21 engages the hook and the bracket to hold the hook in platen locking position, and to return the hook to such position when free to do 80 so. The nose of the hook is shaped at 22 to permit the pin 18 to cam it backward until the pin can pass under the nose, thereby making the locking operation automatic 85 when the platen frame is swung down to normal position. A tooth 23 on the hook may serve to determine the return throw, and normal position of the platen, in conjunction with a pin or stop 24 on the right-hand end carriage piece 14, against which 90 the arm 12 strikes when the platen is thrown down.

To effect the line-space feed or rotation of the platen, there are provided the usual hand wheel 25 and ratchet wheel 26, both 95 fast to a short shaft 27, mounted to rotate in the left-hand end piece 14 of the carriage. In printing position, the shaft 27 is concentric with the platen shaft 11. The ratchet 26 is actuated by a pawl 28 on a 100 slide 29 which may be operated, in Underwood typewriting machines, by a line-space lever (not shown). A spring pawl 28^a, holds the ratchet wheel and platen against 105 accidental displacement. The driving connection between the shaft 27, whose axis does not shift, and the platen axle 11, which swings from one to another position, consists of gears 30, 31 and 32. The gear 30 is fast to the shaft 27; the gear 31 is fast 110 to the platen shaft 11, and is of the same size and number of teeth as gear 30; and the gear 32 is loose on the shaft 13 around 115 which the platen swings, and has a face of sufficient width simultaneously to mesh with gears 30 and 31. A driving connection between the shaft 27 and the platen is thus maintained.

In the patent to Wernery & Smith, above referred to, it is shown that in the operation 120 of removing a printed length of the web, and in readjusting the web for printing the next length, the platen is swung up from printing position to a position away from the feed rolls, so that the web no longer 125 wraps around the platen, but may be moved freely in substantially a straight line from the back to the front of the machine. When the platen is in this position, the carbon sheets between the plies or folds of the sec- 130

tion of the web to be removed, are drawn back into the length or section of web next to be printed; and, after removal of a length of the web, the platen is returned to its normal position against the feed rolls.

The web is preferably in a single piece, fan-folded longitudinally, to provide for several copies when carbon sheets are interleaved with the folds. It may also be in crosswise fan-folded condition before being fed into the machine to permit of compactness and convenience in handling, or it may be fed from a roll. It is fed into the machine over a bar 33 at the rear of a table 34, shown as formed of tubing. The rear bar 33 is connected with a front bar 35 by side bars 36 and intermediate bars 37. The front bar 35, (see Fig. 3), is hollow, and through it passes a rod 38 carried by ears 39 on brackets 40 on the platen carriage. Screws 41 secure the table against longitudinal displacement on the rod 38. Springs 42, between the ends of the bar 35 and the ears 39, hold the bar 35 so that the table 34 may have letter feed and return movement with the platen carriage, but nevertheless yield somewhat to act as cushions or shock absorbers for the table when the latter is thrown a distance with the platen, as for instance in tabulating. The length of the rod 38 is such as to permit some movement thereof relatively to the ears 39, to allow for this cushioning action, without disconnection of the rod 38 from the ears 39. The springs 42 also obviate the necessity of nicety of fitting of the bar 35 to the platen carriage. From the side rails 36 depend arms 43 carrying rolls 44 which ride, and support the table on a rail 45, carried by a framework 46, secured to, or forming part of the main frame of the machine.

The web is led across the table and over the front end thereof behind the platen, whence it is passed down between the platen and the pressure rolls 16 and 15, and thence up across the printing line at the type T, and onto a paper shelf 48 forming part of the swinging platen frame carried by the arms 12. To the shelf 48 is secured a gage 50 in the form of a bar 49, having adjustably mounted thereon a gage piece 50. The latter is a bent metal strip having openings through which the bar 49 passes, and having an offset portion against which the web can be drawn in measuring the length of the sheet to be cut from the web at the cutter 51. The cutter is shown as a blade fast to a sleeve 52 which is loose on the shaft 53. A finger piece 53, also fast to the sleeve 52, is used to swing the cutter against the web when a measured length of the latter is to be removed. A spring 54 holds the cutter in normal position away from the web, and returns the cutter to that position when the finger piece 53 is released. When

the platen is thrown up to release the web, and the web is drawn forward to the gage piece 50, preliminary to cutting, the hold of the several parts on the web is released, with the consequence that the web in front of the platen may be rocked or turned from true position, and may be cut other than squarely, or perpendicularly to the side edges of the web, unless care is used in alining the leading edge at the gage, or unless some device is employed for assisting in positioning the web. For this latter purpose there is secured to the under side of a brace or cross piece 55, on the swinging frame, a guide 56 which is brought up and over the top of the paper shelf, and presents at the front of the latter a blade or guiding portion 57 (see Figs. 4 and 9) for the side edge of the web. The guide 56 has a hole through it to receive any one of several screws 58, positioned at intervals along the brace 55, according to the width of web employed; and a thumb nut 59 threads onto the screws for detachably securing the guide in selected position. Ears 60 on the guide, by engagement with the edge of the brace, prevent the guide from being tipped out of correct position, and aid in the proper setting of the guide.

It has been stated that the web is folded longitudinally so that a plurality of copies may be made at a time by the use of carbon sheets. These carbon sheets, as above stated, are drawn back from the written portion of the web, into the length thereof next to be written, at the time the web is released, and before it is cut. For permitting forward line-space feed of the carbon with the web, and for withdrawing the carbon sheets from the written to the next unwritten section of the web, there is provided a carriage to which the rear ends of the carbon sheets are attached. This carriage, (see Figs. 1 and 6) consists of a rectangular plate 61, cut away at 62 for lightness, and having at each corner an ear 63 on which is mounted a grooved roller 64. The rollers 64 ride on rails 65 which are attached by screws to the tops of the side bars 36 of the table. The carbon sheets 66 are not directly attached to the main body of the carriage 61, but are attached to interchangeable plates 66, (see Fig. 5), near each side of which is a dowel 67 which, when the plate 66 is properly placed on the carriage 61, registers with, and passes through, a hole 68 in the carriage plate 61. The dowels 67 are grooved at 69 below the plate 66, to receive blades 70 which carry finger pieces 71 by means of which the blades may be swung on pivot pins 72, on the plate 61, into and out of interlocking engagement with the grooves 69 in the dowels, thereby serving as means for locking the plate 66 to the plate 61.

On the plate 66 at each side of the carriage is a stepped block 74. Fingers or clips 75, to each of which one carbon sheet may be attached, are secured to the steps 76 of the blocks 74 by thumb screws 77 which also hold clamps 78 between which and the fingers 75 the rear edges of the carbon sheets are held. The fingers 75 are staggered; alternate fingers being secured to the same side of the carriage, so that the fingers may lie in the oppositely directed fan-folds of the web. The steps 76 space the several folds of the web so that the fingers which hold the carbon sheets may not bind the web. The web, therefore, as soon as it reaches the carriage 61 becomes interleaved with the carbon sheets, the rear edges of which are held and the front edges of which are free, except that they are clamped between the folds of the web at the platen by the pressure rolls 15 and 16. Release of this pressure, on lifting the platen, permits retraction of the carriage, with the carbon sheets, relatively to the web; and a handle 79 on the plate 66 serves as a means for throwing back the carriage 61. The handle 79 also serves as a means for lifting the plate 66 from the carriage 61 when the locking blades 70 are thrown out, so that one plate 66 with the web and carbons already in place thereon, may be substituted for another, thereby avoiding the delay of removing and replacing carbon sheets on the webs where a quick change from one web form to another is desired.

One of the rails 65 has scale or gage markings 80 thereon so that the backward throw of the carriage 61 may be accurately determined in accordance with the length of the form on the web, thus assuring proper positioning of the carbon sheets as the successive form sheets or lengths are removed. For example, if the form on the web be eight inches in length, the holder carriage should be returned to the graduation marked "8", in which event there will be no chance of cutting off part of the carbon sheets with the length of web about to be removed. For stopping the carriage at the proper position on each return throw of the same, there is provided a stop 81, (see Figs. 1 and 7). The Fig. 7 form of this stop consists of a yoke 82 adapted to be set over the rail which bears the scale 80, and to be slid along the same 55 to any desired position thereon. One part 83 of the yoke is grooved at 84 to receive the inside rail edge. The outside edge of the rail engages a groove 85 in a shoe 85^a or a plunger 86, which passes through the yoke 60 to the outside thereof, and the end of which is adapted to be engaged by a cam 87 on a finger lever 88, pivoted at 89 to an extension 90 of the yoke. By throwing the finger piece 88 one way or the other, the plunger 86 is forced in, to grip the rail and lock the 65

stop in place, or is released to permit readjustment of the position of the stop. The Fig. 1 form of the stop resembles the Fig. 7 form, except that instead of the plunger and cam lever, a screw 91 is threaded through one side of the yoke and may be turned inward by a handle 92 to bear upon a clamp piece or shoe 93 similar in its action to the shoe 85^a on the plunger 86. A lug 73 on the carriage coöperates with the stop 81 to arrest the carriage.

In filling in forms in a fan-fold machine, the entries are sometimes long and sometimes short. If there are very many short entries, only one portion of the carbon sheet 80 becomes used, and that is used so much that the sheet becomes worn out at that spot while the main portion of the sheet remains practically unused and is wasted. The portion of the carbon which is to be used in 85 writing the successive forms may be accurately predetermined without repeated attention on the part of the operator at every operation; and this is done by first setting the carbon sheet stop 81. Moreover, the initial position of the carbon may be shifted from an eighth to a sixth of an inch by 90 slight readjustment of said stop 81, thereby bringing the lines of use of the carbons between the former lines of use, thus doubling 95 the life of the carbons. All danger of the lower portions of the carbons being accidentally torn off with the written forms is eliminated, since the operator merely has to shift the carbons back as far as they will go.

Further substantial advantages are gained by providing a machine not only with interchangeable carbon-carrying plates 66, but also with the said stop 81, since different carbon-carrying plates may carry different 105 lengths of carbons according to the work in hand; and the operator needs only to readjust the stop 81 for each substitution of carriers, and thereafter simply shift the carbons back as far as they will go and pay no 110 attention to the length of the carbons or attempt to measure with his eye at each stroke the extent or backward shifting of the carbons. The scale 80 is an advantage, because where the operator has different 115 lengths of carbons on different carriers, it is only necessary for him when substituting one set of carbons for another to shift the stop 81 to the corresponding position as indicated on the scale; and in each case he 120 may also make a slight displacement of the stop as may become desirable to shift the lines of use in the same section of the carbon.

Side gages or guides for the web, in its 125 passage across the table, are provided. One set of these is carried by the carbon holding plate 66, and comprises L shaped members 94, the uprights 95 of which form the web guiding surfaces. These L shaped members 130

are carried by and are preferably integral with strips or plates 96, slotted at 97 for the passage therethrough of thumb screws 98, which are threaded into the backs of the 5 stepped blocks 74. The screws 98 have shoulders 99 so that, by turning the screws in or out, the plates 96 may be clamped in set position, or may be released to be slid on the blocks 74 to any setting according to 10 the width of the web. Flanges 100 on the blocks support the lower edges of the plates 96 to maintain the guide pieces 95 in vertical position. The plates 96 also have offsets 101 at their ends which by engagement 15 with the sides of the blocks 74, prevent the plates 96 from being thrown inward against the screws 98 in such manner as to injure the latter.

Another set of lateral guides or gages for 20 the web is found on a bar 102 rigidly supported by arms 103 from the rear bar 33 of the table. These guides comprise upright plates 104 and 105, each fast to a sleeve 106 slidable along the bar 102, (see Fig. 2). The 25 bar 102, which is shown as a tube, is perforated at 107 at intervals therealong to receive locking pins 108 which are shiftable in and out of the sleeves 106, and which, by projecting into the bar 102, hold the guides 30 in place. Leaf springs 109 embrace the sleeves 106, and each has one end fixedly secured to the sleeve by a screw 110. The springs are slotted circumferentially thereof at 111 for the passage therethrough of headed screws 112 carried by the sleeves. The 35 heads of the screws 112 hold the underlying ends of the springs to the sleeves, but not tightly enough to prevent free movement of the free ends of the springs circumferentially of the sleeve within the limits defined by the slots 111. The pins 108 also 40 pass through circumferential slots in the springs, and are grooved or shouldered to receive or engage the springs, so that when 45 the pin is pulled out, the spring is drawn with it, within the limit defined by the slot 111 and screw 112; so that when the pin 108 is released, it is drawn inward by the spring, and by the latter is held in place in 50 the selected hole 107.

The left-hand guide 105 has formed in conjunction therewith, a clamp which can be turned down against the web to hold the web from slipping or being displaced when 55 the carbons are being interleaved, or whenever the web is released from the platen and is not held by hand. This clamp consists of a finger 113 horizontally offset from the guide 105. The left-hand sleeve 106 is not 60 only slidable along the bar 102, but may be turned thereon to bring the finger 113 to the web. The front of the bar 102, at the left-hand side of the table, is also perforated at points 114, so that when the finger 113 is 65 swung to web-engaging position it may be

locked in such position by entry of the pin 108 in whichever of the holes 114 accords to the set position of the guide along the bar.

It has been stated that the web is preferably in a single piece, fan-folded for a multiplicity of copies. Along the side edges or folds, such webs are ordinarily perforated to facilitate separation of one copy from another of the written and separated form sheets or lengths. It has been proposed to 70 effect this separation mechanically in the machine, and for this purpose the free or distal ends of the clips or fingers 75, which hold the carbon sheets, have been provided with cutters 115 in the form of beads or 75 pins which are rearwardly and inwardly inclined, and which cross the perforated edges or folds of the web. As the carriage 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 - transfer material to be used in conjunction with said web, means for shifting said carriage away from the platen to move the transfer material along the web to successive placements thereon, a rail on which the carriage has its line-space and return movement on said table, graduations on said rail for determining the proper return movement to be given the carriage in replacing the transfer material on the web, and a stop shiftable along said graduated rail and lockable in selected position thereon to arrest the carriage on the return throw of the latter.
- 15 3. In a typewriting machine, the combination of a platen, a table over which a web may be guided to the platen, and means for regulating the wear of transfer material inserted between plies of the web, including a carriage movable on said table toward and from the platen, means on said carriage for the attachment thereto of transfer material to be used in conjunction with said web, means for shifting said carriage away from the platen to move the transfer material along the web to successive placements thereon, a rail on which the carriage has its line-space and return movement on said table, and a stop shiftable along said rail and lockable in selected positions thereon to arrest the carriage on the return throw of the latter.
- 20 4. In a typewriting machine, a platen, a platen carriage, means for effecting letter-feed and return movement of the platen carriage, a table over which work-pieces may be fed to the platen, brackets on the platen carriage, a rod loosely supported in eyes in said brackets, a sleeve fast to said table and to said rod, and springs holding said sleeve and rod in normally fixed position with respect to said brackets, but yielding to cushion the table when the latter is thrown with the platen carriage.
- 25 5. In a typewriting machine, a platen, means for feeding a fan-folded web to the platen, means for releasing the web from the platen, a table over which the web is fed to the platen, a carriage movable on said table toward and away from the platen, clips or fingers on said carriage for the attachment thereto of sheets of transfer material to be thereby held interleaved with the folds of the web so as to receive a line-space feed with the web, means for shifting the carriage away from the platen to move the transfer material back along the web to another placement thereon when the web is released after a length thereof has been written, means on said clips or fingers for cutting or separating, one from another, for a distance therealong, the folds of the web when the carriage receives such return movement, and means for preventing binding of said clips or fingers on the web as

the same are moved along the web on such return movement.

6. In a typewriting machine, a platen, means for feeding a fan-folded web to the platen, means for releasing the web from the platen, a table over which the web is fed to the platen, a carriage movable on said table toward and away from the platen, clips or fingers on said carriage for the attachment thereto of sheets of transfer material to be thereby held interleaved with the folds of the web so as to receive a line-space feed with the web, means for shifting the carriage away from the platen to move the transfer material back along the web to another placement thereon when the web is released after a length thereof has been written, means on said clips or fingers for cutting or separating, one from another, for a distance therealong, the folds of the web when the carriage receives such return movement, and separating devices carried by said clips or fingers for holding the same apart when said carriage receives its return movement along the web.

7. In a typewriting machine, a platen, means for feeding a fan-folded web to the platen, means for releasing the web from the platen, a table over which the web is fed to the platen, a carriage movable on said table toward and away from the platen, flexible clips or fingers stepped from one another on said carriage for the attachment thereto of sheets of transfer material to be thereby held interleaved with the folds of the web so as to receive a line-space feed with the web, means for shifting the carriage away from the platen to move the transfer material back along the web to another placement thereon when the web is released after a length thereof has been written, means on said clips or fingers for cutting, or separating, one from another, for a distance therealong, the folds of the web when the carriage receives such return movement, and lugs carried by said clips or fingers for holding the same from movement toward the web when said carriage receives its return movement along the web.

8. In a typewriting machine, a platen, means for feeding a fan-folded web to the platen, means for releasing the web from the platen, a table over which the web is fed to the platen, a carriage movable on said table toward and away from the platen, flexible clips or fingers stepped from one another on said carriage for the attachment thereto of sheets of transfer material to be hereby held interleaved with the folds of the web so as to receive a line-space feed with the web, means for shifting the carriage away from the platen to move the transfer material back along the web to another placement thereon when the web is released after a length thereof has been written, and means

for preventing binding of said clips or fingers on the web as the same are moved along the web on such return movement.

9. In a typewriting machine, a platen, 5 means for feeding a fan-folded web to the platen, means for releasing the web from the platen, a table over which the web is fed to the platen, a carriage movable on said table toward and away from the platen, flexible 10 clips or fingers stepped from one another on said carriage for the attachment thereto of sheets of transfer material to be thereby held interleaved with the folds of the web so as to receive a line-space feed with the 15 web, means for shifting the carriage away from the platen to move the transfer material back along the web to another placement thereon when the web is released after a length thereof has been written, and separating devices carried by said clips or fingers 20 for holding the same from movement toward the web when said carriage receives its return movement along the web.

10. In a typewriting machine, a platen, 25 means for feeding a fan-folded web to the platen, means for releasing the web from the platen, a table over which the web is fed to the platen, a carriage movable on said table toward and away from the platen, flexible 30 clips or fingers stepped from one another on said carriage for the attachment thereto of sheets of transfer material to be thereby held interleaved with the folds of the web so as to receive a line-space feed with the 35 web, said clips or fingers being fixed at one end and free at the other end thereof, and extending in oppositely directed groups into the oppositely directed fan-folds of the web, means for shifting the carriage away from 40 the platen to move the transfer material back along the web to another placement thereon when the web is released after a length thereof has been written, means on said clips or fingers for cutting, or separating, one 45 from another, for a distance therealong, the folds of the web when the carriage receives such return movement, and means carried by the free ends of the clips or fingers for supporting the same above the fixed ends of 50 the adjacent fingers to maintain the spacing of the fingers when the carriage receives its return movement.

11. The combination with a platen, of 55 means for feeding a work-piece in a plurality of plies to the platen, means for holding transfer material between the plies of the work-piece as the latter is fed to the platen and for shifting the transfer material backward along the work-piece to successive 60 placements thereon, a carriage on which said holder is detachably mounted to permit of interchangeability of such holders, with the work-piece and transfer material thereon, and a latch for locking the holder to the 65 carriage.

12. The combination with a platen, of means for feeding a work-piece in a plurality of plies to the platen, means for holding transfer material between the plies of the work-piece as the latter is fed to the platen 70 and for shifting the transfer material backward along the work-piece to successive placements thereon, a carriage on which said holder is detachably mounted to permit of interchangeability of such holders, with the 75 work-piece and transfer material thereon, and means movable while the holder is in place on the carriage for locking the holder to the carriage and releasing the same therefrom.

13. The combination with a platen, of means for feeding a work-piece in a plurality of plies to the platen, means for holding transfer material between the plies of the work-piece as the latter is fed to the platen 80 and for shifting the transfer material backward along the work-piece to successive placements thereon, a carriage on which said holder is detachably mounted to permit of interchangeability of such holders, with the 85 work-piece and transfer material thereon, and a pivoted finger on the carriage for locking the holder thereto.

14. The combination with a platen, of means for feeding a work-piece in a plurality of plies to the platen, means for holding transfer material between the plies of the work-piece as the latter is fed to the platen and for shifting the transfer material backward along the work-piece to successive 90 placements thereon, a carriage on which said holder is detachably mounted to permit of interchangeability of such holders, with the work-piece and transfer material thereon, a dowel on one of said detachably connected elements interlocking with holes in the other of said detachably connected elements, and a movable finger on the element having said holes therein for engaging said 95 dowel to lock and unlock said elements. 100

15. The combination with a platen, of means for feeding a work-piece in a plurality of plies to the platen, a table over which the work-piece is fed to the platen, a carriage movable on said table toward and away from the platen, a detachable holder on said carriage for holding transfer material between the plies of the work-piece as the latter is fed to the platen and for shifting the transfer material backward along 110 the work-piece to successive placements thereon, and guides on said holder for the side edges of the work-piece. 115

16. The combination with a platen, of means for feeding a work-piece in a plurality of plies to the platen, a table over which the work-piece is fed to the platen, a carriage movable on said table toward and away from the platen, a detachable holder on said carriage for holding transfer mate- 125 130

rial between the plies of the work-piece as the latter is fed to the platen and for shifting the transfer material backward along the work-piece to successive placements thereon, and guides on said holder for the side edges of the work-piece, said guides being adjustable to accommodate work-pieces of different widths.

17. The combination with a platen, of means for feeding a work-piece in a plurality of plies to the platen, a table over which the work-piece is fed to the platen, a carriage movable on said table toward and away from the platen, a detachable holder on said carriage for holding transfer material between the plies of the work-piece as the latter is fed to the platen and for shifting the transfer material backward along the work-piece to successive placements thereon, guides on said holder for the side edges of the work-piece, and guides on the receiving end of the table for the side edges of the work-piece.

18. In a typewriting machine, the combination of a platen, a web guide, and means for regulating the wear of transfer material inserted between plies of the web, including a carriage movable toward and from the platen, means on said carriage for the attachment thereto of transfer material to be

used in conjunction with said web, means for shifting said carriage away from the platen to move the transfer material along the web to successive placements thereon, and a stop shiftable to selected positions to arrest the transfer material carriage on the return throw of the latter.

19. In a typewriting machine, the combination of a platen, means whereby a web may be guided to the platen, and means for regulating the wear of transfer material inserted between plies of the webs, including a carrier movable to accommodate the movement of the interleaved transfer material to the platen, means on said carrier for the attachment thereto of superposed sheets of transfer material to be used in conjunction with said web, means for moving said carrier relatively to the platen to move the transfer material along the web to successive placements thereon, and shiftable means to coöperate with said carrier to vary the place of wear upon the transfer material by variably predetermining the initial position of said carrier.
